UNITED STATES PATENT OFFICE.

BERNARD HELD, OF PHILADELPHIA, PENNSYLVANIA.

DESIGN FOR A SHOE-FASTENER.

50,473.

Specification for Design.

Patented Mar. 20, 1917.

Application filed July 14, 1916. Serial No. 109,399. Term of patent 14 years.

To all whom it may concern:

Be it known that I, BERNARD HELD, a citizen of the Republic of France, having declared my invention of becoming a citizen of the United States, residing at Philadelphia, in the county of Philadelphia and State of Pennsylvania, have invented a new, original, and ornamental Design for a Shoe-Fastener, of which the following is a specification, reference being had to the accompanying drawings.

In the drawings, Figure I, shows in dotted lines a shoe having fasteners made according to my design applied thereto.

Fig. II, is a view of a fastener constructed according to my design.

The fastener comprises a central elastic band 2, and rings 3, 3. Tabs 4, 4, are fixed to each ring on the side opposite, where the ring engages the central elastic band, and these tabs are made to conform in width and design with the central elastic band, and are cut with squared edges as shown. When applied the shoe rings 3, engage hooks 1, of the shoe, as shown in Fig. I.

I claim:

The ornamental design for a shoe fastener, as shown and described.

BERNARD HELD.
